MELVIN L. SEVERY, OF LOS ANGELES, CALIFORNIA, ASSIGNOR TO THE VOCALSEVRO COMPANY, OF LOS ANGELES, CALIFORNIA, A CORPORATION OF DELAWARE

METHOD OF AND MEANS FOR CONTROLLING ELECTRICAL AND MAGNETIC PULSATIONS

Application filed June 19, 1931. Serial No. 545,611.

This invention relates more particularly to the conversion of direct currents of electricity into rhythmical pulsations, and one of its chief uses is in that type of musical instruments where electromagnets are employed to generate the tone-producing impulses.

Other important objects of the invention are to increase the efficiency of operation to an extent which makes possible a decrease in the operating voltage with the same magnet windings; more perfect operation; and greater durability of the current-pulsating mechanism.

Another important object of the invention is the suppression, to a negligible point, of the arcing which ordinarily occurs at the brushes of current-pulsating mechanisms.

In U. S. Patent No. 1,104,939, entitled "Electric musical instrument", issued to M. L. Severy and G. B. Sinclair and dated July 28, 1914, a commutating mechanism is shown and claimed, with conducting brush-traversed sections shorter than the non-conducting sections by at least the lap of the brush. As there stated, the purpose of such construction was that current should never be in the associated magnet for more than half of the time; that is to say, that during operation, the live instants of the magnet should never exceed the dead instants.

When considering a magnet's attraction of its armature in rhythm with the pitch of some note of the musical scale, it is inevitable that the periods of approach to and recession from the core should be thought equal in time, and it is most natural that it should be considered that this dictated, where a commutator is used, conducting sections which should at least be as small as the non-conducting sections, to the end that the live instants of the associated magnets should never exceed in duration the dead instants thereof. This conclusion, natural as it seems, I have discovered to be most erroneous, as will appear as this specification proceeds.

In the drawing:

Fig. 1 is a diagrammatic view showing, partly in elevation and partly in section, a

commutating mechanism embodying my invention and a speaking unit actuated thereby, the driving means for the commutator being omitted;

Fig. 2 is a view of said speaking unit, taken at right angles to that shown in Fig. 1;

Fig. 3 shows an enlarged segmental portion of a commutator ring, disk or member having a different number of conducting and non-conducting sections from that shown in Fig. 1.

In Fig. 1 the numeral 1 indicates a section of a commutator embodying the present invention; 2 the non-conducting or high resistance areas; and 3 the conducting or low resistance areas or teeth, which are usually integral with the commutator section 1. A brush 4 contacts with the periphery of the commutator section, another brush 5 bearing upon the central shaft 6, or being otherwise constantly in electrical communication with commutator section 1. 7 indicates a source of electricity and 8 a pole thereof, in this case a positive pole. A contacting member 9 is carried by a key 10 and adapted to contact with the pole 8 upon the pressure of a key 10 of the manual. This showing is purely diagrammatic, all unnecessary details being omitted. A wire 11 joined to contact 9 at one end leads to the magnet 17, from which another wire 16 connects with wire 16^a leading to brush 4 through which and the commutator section 1 and brush 5, the circuit is completed to the negative pole of the source of current 7. A condenser 12 and a resistance 13, preferably non-inductive, in shunt therewith, are introduced for the purpose of suppressing the arcs when brush 4 leaves a conducting area of commutator section 1. This condenser 12 may be of ordinary form; it may be of the liquid or dry electrolytic type; or it may be some other form of capacitor, and may be employed with or without a resistance in shunt or otherwise. Moreover, the condenser may be, and in some cases I have found it well that it should be, across the magnet instead of across the break. I have indicated this location in dotted line at 15 with 14 as a resistance.

As seen in Figs. 1 and 2, the magnet 17 is provided with a core 18 axially adjustable by nuts 19, 20, said core opposing an armature 38 threaded into the ribbed plunger-type diaphragm 23 held flexibly at the end of resonator 21 by the membrane 23^a of rubber-cloth, leather, or other suitable material. This membrane is secured to resonator 21 at its edges by a metallic ring 10 or annulus 39, here shown of trough-like form in cross section, and fastened to resonator 21 by screws. The membrane 23^a is secured to the edges of the plunger-diaphragm 23 by a circular clamping ring or 15 band 25 secured by screws to the projecting edge 24 of said diaphragm. Diaphragm 23 is thus left free to reciprocate vertically under the action of magnet 17, upon the flexible bar 26 to which said diaphragm is 20 fastened and by which it is carried. Pins 27 pass freely through flexible bar 26 and are firmly seated in the adjustable members 28, so that when the adjusting screws 32, the inner ends of which bear against the 25 fixed frame or magnet-housing 35, are turned in proper direction to move the upper ends of supporting members 28 outward, bar 26 will be put under longitudinal stress or tension, thus adjusting it, at least 30 roughly, to its load and periodicity. Any obliquity or deviation from vertical position of the supporting members 28 incident to such adjustment by screws 32, will be corrected by very slightly backing off the nuts 35 30 carried by the outer ends of the fixed rods 29, which rods carry the supporting members 28, and are themselves carried by the fixed frame 35.

This construction makes it possible to 40 keep a straight draft upon flexible bar 26 during its various adjustments. Clamping bolts and nuts 40, 41 limit the free length of bar 26 and secure it against rattling. The bar-adjusting members 28 are arranged to 45 afford two adjustments, one at either end, so that their pull may be kept sensibly normal to bar 26 upon which they act. The adjustable magnet-housing 35 is formed or furnished with bracket members 37, per- 50 forated to receive rods 31, each threaded at its upper end and screwed into tapped lugs 22^a projecting inwardly from plates 22 secured by screws or other fastenings to the base of resonator 21. To prevent the loosening of the rods 31, set screws may be em- 55 ployed as shown in Fig. 1. The lower ends of rods 31 pass through the perforated horizontal portion of the bracket members 37, as best seen in Fig. 2, said rods being pro- 60 vided at their lower threaded ends with nuts 33 placed one above and another below each of said plates. By proper adjustment of said nuts 33, the magnet housing may be raised or lowered as desired, and securely 65 held in fixed relation to the diaphragm 23

and connected parts. The plates 22 may advantageously be formed with ribs or flanges 34 to facilitate their positioning on the base of the resonator, and to afford additional stiffness.

The construction above set forth has proven quite satisfactory, but may be varied as found expedient.

Fig. 3 shows on an enlarged scale a commutator member 1 having more teeth than that shown in Fig. 1, this affording somewhat different time relation between the dead and the live instants of the associated magnet as will be obvious.

A speaking magnet of ten ohms resistance 80 operating at thirty volts would take three amperes of current if there were no interruption or pulsation therein. I have found, however, that when the current is interrupted, say, thirty-two times a second with the dead instants and the live instants of the magnet equal in duration, the current will drop to a small fraction of the former amount, for example, to four-tenths of an ampere. Under these conditions the speaking unit will be actuated rhythmically so far as the energizing magnet is concerned, and the same would be true if the dead instants of the magnet were of twice the duration of the live instants. In the latter case, 90 however, there would be a very great decrease in efficiency. It has been the common thought that if the live instants of a magnet exceeded in time the dead instants thereof, there would be a "hold-over" or a tendency 100 to retain the magnet near the core when it ought to be freely receding therefrom, thus decreasing the efficiency of the magnet and, as it were, stifling the resulting tone. I have 105 found this seemingly natural conclusion to be entirely erroneous, and many and most carefully conducted tests have clearly demonstrated that not only may the live instants of the magnet be increased in time beyond the time of the dead instants without hurting the efficiency or marring the 110 quality of the tone, but that the efficiency and the quality both are greatly enhanced by this method of procedure. It has been 115 found that, under certain conditions, a live instant of 80% and a dead instant of 20% of the total time of a vibration gives a most excellent result, showing a great increase in current taken, in efficiency, and in quality 120 of results.

It has also been discovered that the same magnet 17, Figs. 1 and 2, behaves one way when in its housing, as shown, and another way when operated outside of said housing. In the housing it is provided with a most excellent return circuit, the housing being usually of cast iron and bar 26 being of steel, with the armature or part 38 also of magnetic metal. This would be expected to give a stronger pull than when the return 130

circuit is through a long air-gap. It has been ascertained, however, that this condition of affairs decreases somewhat the current consumption of the magnet, and that it has a pronounced effect upon the arc at the commutator, which, tested without a condenser, it seems to cut down in proportion to the nearness of the approach of the armature to the core. If the armature be permitted to remain in contact with the core, the arc is decreased, judging by its appearance, from 80 to 90 per cent, and at practical working distance the decrease in the arc is very noticeable over what it is with the same magnet without housing and metallic return circuit throughout all but a trifling portion of its distance from pole to pole. The suppression of the arcs being the largest factor in the efficient life of commutators and brushes, this discovery and method of applying it are of great importance, since when it is used there is less left for condensers, electrolytic cells, capacitors, or the like to accomplish in rendering the arcs negligible.

Furthermore, the method herein set forth produces a sound-wave of better form as well as of greater power and efficiency. In a musical instrument, say of seven octaves, it is customary to cover a vibrational range of from 32 to nearly 4,000 per second and, since it is desirable to use commutators of reasonably small diameter for reasons of cost and compactness, it will readily be seen that the commutating members serving the higher notes must of necessity have more and therefore much smaller "teeth" than those serving the lower notes. Moreover, the amount of current taken by a magnet varies greatly with the period of its pulsations, being less the more rapid these are. By reason of these facts I wish it distinctly understood that I do not confine myself to any one ratio of dead and live instants in the magnets, as the ratio of those magnets serving notes of high pitch will preferably be different from that of those magnets serving notes of low pitch.

I have found that a live instant of 80% and a dead instant of 20% is well suited to a very low note, but the smallness of the "teeth" of commutator members serving very high pitches together with the lap of brushes of sufficient thickness for stability, renders it advisable if not imperative with commutators of moderate diameter serving such high notes, to decrease this 80% live instant to some extent, though preferably keeping it as large as conditions will permit. In cases where the size of commutators may be increased sufficiently to permit it, this 80% live instant is preferably employed even with the very highest note, much better results being thus secured. However, in an instrument built to serve the needs of the

general public in the matter not only of results but of price and size, it is preferred, ordinarily, to vary the live instants as the pitch ascends, though not necessarily with every note of the scale but rather by groups or sections.

It is obvious that a current could be pulsated without at any time entirely stopping the flow thereof, and that a current of this character when energizing a magnet would result, not in live and dead instants of said magnet, but in instants more alive and less alive, for which reason it is expressly to be understood that wherever in this specification or its associated claims the terms "live" and "dead" instants are used, they are specifically meant to include instants which are "more alive" and those which are "less alive" though not necessarily entirely "dead".

It is also to be understood that wherever in this specification or its associated claims, pulsations in the current are referred to, this has been done with the express intention of covering rhythmical current changes including actual make and break, as well as rhythmical variations in a current some of which is continuously flowing.

In order to avoid complicating the showing of this application, and for the further reason that it is an art so well known, all unnecessary details, including the driving means for the commutating mechanism, have been omitted, the drawing being largely diagrammatic. It is to be understood, of course, that the commutators or their equivalents are to be driven by carefully timed speed mechanism, suitable types of which are shown in other patents granted to me and in pending applications filed in my name.

Furthermore, no attempt has been made to show the exact construction of the commutating mechanism, its variously sized teeth, and the like. It should be stated, however, that a conducting substance is commonly mixed with the cement or other material used to fill the non-conducting areas of the commutator, thus lowering their resistance. It is to be understood, therefore, that when conducting and non-conducting areas of the commutator are referred to, this phraseology includes also areas of relatively low and high resistance, respectively, since there are distinct advantages in lowering the resistance of the non-conducting areas by the admixture of the conducting substance as stated, and this construction is ordinarily employed.

What is claimed is:—

1. The herein-described method of increasing the efficiency of a rapidly responsive electromagnet, which consists in creating rhythmical current increments and decrements in the electricity energizing said electromagnet, the said increments being of

- substantially longer duration than the alternate decrements.
2. The herein-described method of increasing the efficiency of rhythmical electrical pulsations delivered to an electromagnet, which consists in making the live instants of the magnet, when in operation, of substantially longer duration than the dead instants thereof.
- 10 3. The herein-described method of producing pulsations in an electric current, which consists in delivering the current to a commutating member co-acting with a brush, said brush and the low-resistance portions of said member traversed thereby being so proportioned that, in operation, the co-acting low-resistance surfaces thereof will be in electrical contact substantially more than half of the time.
- 15 4. The herein-described method of increasing the efficiency of a rapidly responsive electromagnet, which consists in creating rhythmical current increments and decrements in the electricity energizing said electromagnet, through the agency of alternately operative high and low resistance commutator areas associated with a co-acting brush, the low-resistance areas being circumferentially longer than the high
- 20 resistance areas.
5. The herein-described method of increasing the efficiency of sets of rhythmical electrical pulsations, the sets being of different periodicities and delivered to electromagnets, one for each said set, said method consisting in making the live instants of the magnets, when in operation, of substantially longer duration than the dead instants thereof, and in varying the ratio of live
- 25 to dead instants in magnets associated with some of the different periodicities.
- 40 6. The herein-described method of producing pulsations of various frequencies in an electric current, which consists in delivering the current to make-and-break mechanism having a plurality of sections each thereof provided with a co-acting brush, each of said brushes and its associated conducting portions of the mechanism traversed thereby being so proportioned that, in operation, the co-acting conducting surfaces thereof will be in electrical contact substantially more than half of the time, the ratio of the time of contact to non-contact
- 45 varying in different parts of the mechanism producing different periodicities of pulsations.
- 50 7. The herein-described method of altering the wave-form of the magnetic flux of an electromagnet energized by pulsating current, which consists in making the live instants of the electromagnet of substantially longer duration than its dead instants.
- 55 8. The method of producing different magnetic wave-forms and increasing the efficiency of the magnetic fluxes of electromagnets energized by pulsating electric currents having the periodicities of the notes of a musical scale, for use in connection with associated mechanism to produce sounds of said periodicities of vibration, said method consisting in rendering the live instants of the electromagnets of substantially longer duration than their dead instants, and in producing in some of the electro-magnets time-ratios of live to dead instants different from those subsisting in other of said electromagnets.
- 70 9. In an electrical current-pulsating mechanism, means for minimizing arcing and prolonging the periods of energization of said mechanism, comprising a source of direct current and suitable connections, commutating members and associated brushes adapted, when relative motion is produced between them, to cause alternate increments and decrements in the flow of the commutated current, the increments occupying substantially more time than the decrements.
- 75 10. In an electrical current-pulsating mechanism, means for minimizing arcing and prolonging the periods of energization of said mechanism, comprising commutating members having circumferentially distributed areas of alternately high and low resistance material traversed by a brush, the contact of said brush with the areas of low resistance being of substantially longer duration than the contact with those of high
- 80 resistance.
- 90 11. In an electrical current-pulsating mechanism, means for minimizing arcing and prolonging the periods of energization of said mechanism, comprising commutating members having circumferentially distributed areas of alternately high and low resistance material traversed by a brush, the low resistance areas being longer circumferentially than the high resistance areas.
- 95 12. In an electric musical instrument, the combination of a series of resonators each serving to furnish a note of the musical scale; a plunger-diaphragm associated with each resonator and provided with an armature; a magnet supported in proximity to each armature; current-pulsating members each bearing upon its circumference successive areas of alternate high and low resistance material, the low resistance areas being substantially longer in the direction of travel than the high resistance areas; a brush associated and contacting with each of said current-pulsating members; a source of electric current; and electrical connections between the source of current, the several current-pulsating members, and their associated magnets.
- 100 13. The herein-described method of increasing the efficiency and improving the action of a rapidly responsive electromag-
- 110
- 115
- 120
- 125
- 130

net, which consists in creating rhythmical current increments and decrements in the electricity energizing said electromagnet, through the agency of electrically conducting commutator areas of high and low resistance associated with a co-acting brush, the low resistance areas when traversed by said brush in operation, furnishing current increments of longer duration than the alternate current decrements.

14. In an electrical current-pulsating mechanism, circumferentially distributed areas of high and low electrical conductivity traversed by a brush, the current increments produced by the passage of the brush over the areas of high conductivity being of substantially longer duration than the current decrements produced by the passage of the brush over the areas of low conductivity, the last-named areas being formed of a material containing or treated with, an electrically conducting substance.

15. In an electrical current-pulsating mechanism, circumferentially distributed areas of high and low electrical conductivity traversed by a brush, the current increments produced by the passage of the brush over the areas of high conductivity being of substantially longer duration than the current decrements produced by the passage of the brush over the areas of low conductivity, the last-named areas being formed of a material containing, or treated with, a friction-diminishing lubricant.

35. In testimony whereof I have signed my name to this specification.
